CHAIR OR SIMILAR ARTICLE

Hartmut Lohmeyer, Munich, Germany, assignor to Burris
Manufacturing Company, Lincolnton, N.C.

Filed June 14, 1971, Ser. No. 153,153

Term of patent 7 years

Int. Cl. D6—02

U.S. Cl. D6—66

FIG. 1 is a perspective view of a chair showing my new design;

FIG. 2 is a front elevational view of the chair shown in FIG. 1 but on a similar scale;

FIG. 3 is a side elevational view of the chair shown in FIG. 2;

FIG. 4 is a top plan view of the chair shown in FIG. 2;

FIG. 5 is a rear elevational view of the chair shown in FIG. 2.

I claim:

The ornamental design for a chair or similar article, substantially as shown.
